DIGITAL ALARM CLOCK

Hideaki Nagata, Tokyo-to, Japan, assignor to Kabushiki
Kaisha Koparu, Tokyo-to, Japan

Filed June 25, 1973, Ser. No. 373,309

Claims priority, application Japan Dec. 27, 1972

Term of patent 14 years

Int. Cl. D10—01

U.S. Cl. D10—15

FIG. 1

FIG. 2

FIG. 3

FIG. 4

FIG. 1 is a top-front perspective view of a digital alarm clock showing my new design;

FIG. 2 is a left side elevational view thereof, the right side being a mirror image thereto;

FIG. 3 is a rear elevational view thereof; and

FIG. 4 is a bottom plan view thereof.

I claim:

The ornamental design for a digital alarm clock, substantially as shown and described.
